ALTON E. COBB, OF LOS ANGELES, CALIFORNIA.

GAS STOVE.

1,427,069.

Specification of Letters Patent. Patented Aug. 22, 1922.

Application filed February 14, 1921. Serial No. 444,693.

To all whom it may concern:

Be it known that I, ALTON E. COBB, a citizen of the United States, residing at Los Angeles, in the county of Los Angeles 5 and State of California, have invented new and useful Improvements in Gas Stoves, of which the following is a specification.

My invention relates to new and useful improvements in gas stoves of the type generally used for household heating purposes, the principal object of my invention being 10 to provide a relatively simple heating device that utilizes gaseous fuel, said heating device capable of being easily and cheaply 15 produced and very efficient in use.

With the foregoing and other objects in view, my invention consists in certain novel features of construction and arrangement of parts that will be hereinafter more fully described and claimed and illustrated in the 20 accompanying drawings, in which

Fig. 1 is a top plan view of a heater constructed in accordance with my invention.

Fig. 2 is a side elevational view of the 25 heater.

Fig. 3 is a horizontal section taken on the line 3—3 of Fig. 2.

Fig. 4 is a vertical section taken on the line 4—4 of Fig. 1.

Referring by numerals to the accompanying drawing, which illustrates a practical embodiment of my invention, 10 designates the base portion of the heater body, the same being in the form of an upright hollow cylinder, preferably formed of sheet metal and provided adjacent to its lower edge with an 35 annular row of air inlet openings such as 11.

Surmounting the body portion 10 is a truncated member that comprises an inwardly and upwardly inclined wall 12, and formed therein is an opening 13 that is closed by a section of transparent material such as glass or mica, and also formed in this wall is an opening 14 that is normally closed 45 by a hinged or sliding door such as 15. The glazed opening 13 provides means for observing the action of the gas burner positioned in the chamber beneath the member 12, and the opening 14 gives ready access 50 to the burner chamber for the purpose of lighting the burner therein.

Positioned within the cylindrical member 10 is a horizontally disposed ring 16 that is preferably formed of sheet metal, and secured thereto around the opening therein is the lower end of a vertically disposed cylind-

er 17 preferably formed of sheet metal and which extends upwardly through the opening formed by the inclined wall 12. The diameter of cylinder 17 is slightly less than the diameter of the circular opening in the upper end of the inclined annular wall 12, and thus a narrow annular opening 18 is formed between the upper end of member 12 and the wall of cylindrical member 17. 60

Secured to the upper portion of the inclined wall 12 is the lower end of a hollow cylindrical member 19 that is preferably formed of sheet metal the same being slightly larger in diameter than the cylindrical member 17, and the upper ends of the walls of the cylindrical members 17 and 19 are closed by a ring plate 20, preferably formed of sheet metal and inclined upwardly and inwardly from the outer member 19. 70

Leading from the upper end of the annular chamber between members 17 and 19 is a vent pipe 21 that may be led to any desired point, for instance, to a chimney opening. 75

Arranged in the upper portion of the chamber between ring members 12 and 16 and the lower portion of cylindrical member 17 and the upper portion of base member 10, is a burner ring 22 having suitable perforations formed in its upper portion to form jet openings, and leading to said burner ring through inclined wall 12 and from a suitable source of supply is a gas supply pipe 23 in which is located a gas control valve 24 and a suitable device 25 that serves to admit air to pipe 23 and to mix said air with the gas passing through said pipe to the burner ring. 80

In the use of my improved gas heater, 95 valve 24 is opened to permit a combustible mixture of gas and air to pass through pipe 23 to the burner ring and as said gas discharges in jet form from the upper portion of said ring the jets, when ignited, will be 100 directed upwardly and outwardly against the upper portion of the inclined wall or ring 12, thereby heating the same to a high degree, and the heat thereof will be radiated outwardly and upwardly throughout 105 an annular zone adjacent to the lower portion of the heater. The inclined wall or ring serves to deflect the jets of burning gas and the products of combustion upwardly and inwardly against the outer surfaces of cylinder 17, thereby heating the same, and the products of combustion from the burning 110

jets will pass upward through the narrow annular opening 18, thence upwardly through the space between cylindrical members 17 and 18 and finally into and through 5 vent pipe 21.

Thus, the entire upper portion of cylinder 17 will be uniformly heated and the greater portion of this heat will be absorbed by air which passes upwardly through said cylindrical member 17 and which air enters base member 10 through the openings 11 and leaves the heater through the open upper end 10 of cylindrical member 17.

When door 15 is closed, the chamber occupied by the burner ring is practically air tight, and as a result the burner will not give off any odors while in operation, for all the air necessary to support combustion at the jets issuing from the apertures in said burner ring is admitted to said burner ring through air inlet and mixing valve 25.

A gas heater of my improved construction is comparatively simple, is light, strong and durable, can be easily and cheaply produced 25 and is very effective in performing its intended functions.

It will be readily understood that minor changes in the size, form and construction of the various parts of my improved gas 30 heater may be made and substituted for those herein shown and described without departing from the spirit of my invention, the scope of which is set forth in the appended claims.

35 I claim as my invention:

1. In a gas heater, a substantially cylind-

rical upright member through which air is adapted to pass, a substantially air tight burner chamber surrounding the lower portion of said cylindrical member, a burner 40 ring within said air tight chamber, a substantially air tight heating chamber surrounding the upper portion of said cylindrical member and in such manner as to provide a narrow annular opening between the 45 burner chamber and the heating chamber, a gas supply pipe connected to the burner ring, and means in the pipe for supplying air to the burner ring.

2. In a gas heater, a cylindrical base having air inlet openings, a ring within the base, a cylinder sustained on the inner periphery of the ring, a truncated member formed in the upper end of the base and having its small end disposed in spaced relation to the cylinder to provide an annular opening between the member and cylinder, a cylindrical member disposed concentrically of the cylinder and connected to the truncated member, a vent pipe in communication with the upper end of the chamber formed between the cylinder and cylindrical member, a ring plate closing the upper end of said chamber, a burner surrounding the cylinder between the ring and the truncated member, a gas supply pipe connected to the burner, and means in said pipe and exteriorly of the heater for supplying air to the burner.

In testimony whereof I have signed my 70 name to this specification.

ALTON E. COBB.
